(57) **CLAIM**

The ornamental design for a hair extension device, as shown and described.

DESCRIPTION

FIG. 1 is a perspective view of the hair extension device of the present invention showing my new design;

FIG. 2 is a front side elevation view thereof;

FIG. 3 is a back side elevation view thereof;

FIG. 4 is a side elevation view thereof;

FIG. 5 is another side elevation view thereof;

FIG. 6 is top plan view thereof; and,

FIG. 7 is a bottom plan view thereof.

The hair extension device is shown broken away to show indeterminate length and for ease of illustration.
